UNITED STATES PATENT OFFICE.

EDWIN F. BEUGLER, OF BUFFALO, NEW YORK, ASSIGNOR TO E. & B. HOLMES MANUFACTURING CO., OF BUFFALO, NEW YORK, A CORPORATION OF NEW YORK.

MACHINE FOR MAKING BARRELS.

Application filed August 30, 1922. Serial No. 585,131.

To all whom it may concern:

Be it known that I, EDWIN F. BEUGLER, a citizen of the United States, residing in Buffalo, in the county of Erie and State of New York, have invented new and useful Improvements in Machines for Making Barrels, of which the following is a specification.

This invention relates generally to machines for making barrels, but more particularly to a machine for compressing the staves about the head to permit the hoops to be fitted thereon.

One of the objects of the invention is to provide an improved power actuated machine of this character which is simple and compact in construction, and which is efficient in operation and easily controlled.

A further object is to improve the stave-compressing mechanism with a view of contracting the staves uniformly and with equal pressure throughout the circumference of the barrel.

In the accompanying drawings:

25 Figure 1 is a side elevation of a barrel making machine embodying my improvements. Figure 2 is a top plan view thereof. Figure 3 is an enlarged fragmentary horizontal section taken in the plane of line 30 3—3, Fig. 1. Figure 4 is a vertical section on line 4—4, Fig. 3. Figure 5 is a fragmentary transverse vertical section on line 5—5, Fig. 3. Figure 6 is a fragmentary sectional bottom plan view of the parts shown 35 in Fig. 3. Figure 7 is a transverse section on line 7—7, Fig. 2.

Similar characters of reference refer to like parts throughout the several views.

In its general organization the improved 40 machine comprises a base or supporting frame for supporting its working parts, a pair of compressor or contracting arms for compressing the staves of the barrel, a power-actuated mechanism for actuating the 45 compressor arms to contract the staves, and manually-controlled means for controlling said power-actuated mechanism and for releasing the same to effect an expansion of the compressor arms.

50 The supporting frame of the machine may be of any appropriate construction, but as shown in the drawings, the same preferably comprises a base 10 forming a platform at its front end for supporting the barrels to 55 be operated upon, and an upright extension

11 arranged near its rear end for supporting the compressor arms and the actuating mechanism.

12, 12 indicate the compressor arms, which, as shown in Fig. 2, are of substantially semi-circular form so that they together partially encircle the barrel when compressed. These compressor arms overhang the platform portion of the base 10 and are adapted to swing horizontally toward and from one another for compressing the staves of a barrel at a point below its upper end. The opposing rear ends of the arms are pivoted or hinged to an upright post 13 suitably journaled in the upper front portion of the base extension 11. One of these arms is provided with a collar 14 fastened by a set screw 15 to the post while the other arm is provided with a fork 16 loosely fitting the post and embracing said collar.

17 indicates an upright shaft arranged parallel with the post 13 and journaled in suitable bearings formed in the base extension 11 and provided at its upper end with a bell-crank lever 18 having a comparatively long arm 19 and a short arm 20. This bell-crank lever is operatively connected to the compressor arms by toggle links 21, 22 so that when said lever is turned in one direction or the other the arms are caused to swing in a corresponding direction. For this purpose, the links are preferably apertured at their ends and the compressor arms are provided with rearwardly extending lugs or brackets 23 to which the outer ends of the links are pivoted by pins 24 while their inner ends are pivoted by pins 25 to the corresponding arms of a bell crank-lever.

Any suitable means may be employed for transmitting motion to the shaft 17 for the purpose of contracting the compressor arms 12, 12 about the barrel, but as shown in the drawings, this is preferably effected by providing said shaft at its lower end with a worm wheel 26 which is loosely mounted thereon and constantly in mesh with a worm 27 fixed on a horizontal driving shaft 28. The latter is journaled at its ends in bearing brackets 29 mounted on the rear portion of the base 10 of the machine, as shown in Figs. 1 and 2. This driving shaft is provided with tight and loose pulleys 30, 31 which may be connected by a belt (not shown) to any suitable source of power.

The driven shaft 17 is controlled by a friction clutch consisting of a female member 32 formed integrally with the worm wheel 26 and a male member 33 splined on said shaft 5 and movable vertically thereon into and out of engagement with its companion female member. The shifting of the male clutch member into and out of engagement with its female member is effected by a vertically-10 swinging clutch lever 34 fulcrumed at 35 to the upright extension 11 and provided at its rear end with a fork 36 engaging a grooved collar 37 formed on said male clutch member. This rock lever is actuated 15 by a foot lever 38 pivoted at 39 to the left hand side of the base 10 and connected by a link 40 with the front arm of said clutch lever. A coil spring 41 applied to the rear arm of said clutch lever normally tends to 20 hold the clutch in its released or inoperative position. By depressing the foot lever the clutch is moved to its engaged or operative position. In the fully contracted position of the compressor arms about the bar- 25 rel, as shown in Fig. 2, the same are self-locking inasmuch as the pivotal axes of the toggle links 21, 22 are on a dead center line with the axis of the driven shaft 17.

In order to unlock the compressor arms 30 and permit them to be moved to their open or expanded position, shown by dotted lines in Fig. 2, a manually operated device is employed which preferably consists of a releasing member 42 in the form of a bell 35 crank lever turning in a vertical plane and fulcrumed at 43 to the upper rear portion of the base extension 11. This releasing member is adapted to engage its upright rear arm with a rearwardly facing shoulder 44 formed on the short arm 20 of the bell crank lever 18 so as to turn the same in the proper direction to break the dead center 40 position of the toggle links. For the purpose of conveniently actuating the releasing member, a foot lever 45 fulcrumed at 46 is 45 provided, a link 47 serving to operatively connect said foot lever with the horizontal front arm of the releasing member, as shown in Fig. 1.

After the breaking of the toggle connection between the compressor arms and the bell crank lever 18, through the medium of the releasing device 42, a coiled spring 48 is employed for automatically returning 50 said compressor arms to their open or normal position. The ends of this spring are attached to perforated lugs 49 formed on the opposing inner ends of the compressor arms, as shown in Fig. 6.

Means are provided for cushioning the compressor arms at the end of their return movement so as to prevent any undue shock and strain on the same and associated parts. To this end the opposing inner ends of the 60 compressor arms are provided with sockets 65

50 and suitably guided in each of them is a horizontal bolt 51 having a coiled spring 52 encircling the same, said spring bearing at one end against the bottom of the respective socket and at its other end against the 70 bolt head. The heads of the bolts project beyond the opposing open ends of the sockets 50 and are adapted to contact with each other when the compressor arms are automatically opened to the position shown 75 in Fig. 3.

The compressor arms 12 do not themselves touch the barrel, but each arm is provided with a series of curved segmental jaws or plates 53 yieldingly mounted thereon so as 80 to come into contact with the barrel staves when the compressor arms are closed or contracted. Any suitable means may be employed for yieldingly mounting those jaws or plates so that they are permitted a certain range of movement to adapt them to the irregularities in the shape of the barrels. As shown in Figs. 1, 2 and 7, each of the segmental plates is adjustably mounted on a radially movable slide 54 guided in a dovetail way 55 formed in the upper side of the respective compressor arm. An upright fulcrum member or bar 56 is fitted within an outwardly-opening recess 57 formed in a bracket 58 depending from the outer side of 90 said compressor arm and projects upwardly through an opening 59 in the outer end of the slide 54. Extending diagonally through an opening 60 in the fulcrum bar and through an upright slot 61 in the bracket 58 is a bolt 62 and applied to the inner end of the latter is a coiled spring 63 held in place by a washer 64 and nut 65. The purpose of this spring is to permit the segment jaw or plate to adapt itself to irregular barrels, said spring tending constantly to resist the outward movement of said plate.

Briefly stated, the operation of the machine is as follows:

Assume a barrel to be in place on the base 10 and the compressor arms 12, 12 to be in their normal open or expanded position. To close the arms around the barrel, the operator depresses the foot lever 38 to engage the clutch 32, 33 and rotate the toggle-actuating lever 18 from the position shown in Fig. 3 to that shown by full lines in Fig. 2, in which position they are locked, as previously described. The operator now releases the foot lever to disengage the clutch. After applying the end hoop or hoops to the barrel, he depresses the foot lever 45 to break the toggle connection after which the spring 48 causes the compressor arms to be automatically returned to their open position.

Barrels of different sizes may be operated upon by this machine by simply substituting segmental jaws or plates 53 of different sizes.

Upon swinging the compressor arms apart 130

the short arm of the bell crank operating lever swings across the space between the axes of the operating lever and the compressor arms and the long arm of the same 5 moves toward the rear of the axis of the operating lever, thereby compensating for this difference in the position of the arms of the operating lever and causing both compressor arms to be opened and closed uniformly. 10

The mechanism for actuating the compressor arms imparts to them equal strokes so that they move uniformly and simultaneously through the same distance at substantially 15 the same speed, thereby bringing the barrel staves together evenly and truly without danger of breakage. Furthermore, by this arrangement, an infinite amount of power is advantageously applied at the end 20 of the closing stroke of the compressor arms, at a time when the greatest resistance is encountered and a corresponding increase in power is required.

I claim as my invention:

25 1. A barrel making machine, comprising a pair of compressor arms arranged to encircle a barrel and movable about the same axis toward and from each other, and a rotatable bell crank member having arms of 30 different length operatively connected to said compressor arms for actuating them, the shorter arm of said bell crank member playing between its fulcrum and the adjacent part of the machine while the long 35 arm of the same compensates for the difference in direction of the throw imparted to the two arms of the bell crank member.

2. A barrel making machine, comprising a pair of compressor arms arranged to encircle a barrel and movable about the same 40 axis toward and from each other, a bell crank actuating member rotatable in the plane of movement of said compressor arms and having bell crank arms of different length, and a pair of toggle 45 links connecting said bell crank arms with the compressor arms, the shorter arm of said bell crank member playing between its fulcrum and the adjacent part of the machine while the long arm of the same compensates 50 for the difference in direction of the throw imparted to the two arms of the bell crank member.

3. A barrel making machine, comprising a pair of compressor arms movable about a pivot toward and from each other, said arms being provided adjacent their pivot with oppositely-facing sockets, and spring-pressed 55 bolts mounted in said sockets and adapted to engage each other for cushioning the expanding movements of said arms.

4. A barrel making machine comprising a pair of compressor arms pivoted on the same axis, a bell crank operating lever arranged in rear of said arms and having a short arm adapted to swing across the space between the axis of said operating lever and compressor arms, and a long arm adapted to swing toward the rear of the axis of said operating lever, and links connecting the 70 short and long arms of said operating lever with said compressor arms, respectively.

EDWIN F. BEUGLER.
